UNITED STATES PATENT OFFICE.

JAMES G. GRACEY AND ALFRED GFELLER, OF ST. LOUIS, MISSOURI, ASSIGNORS
TO POSITIVE ELEVATOR SAFETY COMPANY, OF ST. LOUIS, MISSOURI,
A CORPORATION OF MISSOURI.

ELEVATOR SAFETY APPLIANCE.

SPECIFICATION forming part of Letters Patent No. 687,621, dated November 26, 1901.

Application filed March 20, 1901. Serial No. 52,271. (No model.)

To all whom it may concern:

Be it known that we, JAMES G. GRACEY and ALFRED GFELLER, citizens of the United States, residing at St. Louis, State of Missouri, have invented certain new and useful Improvements in Elevator Safety Appliances, of which the following is a full, clear, and exact description, reference being had to the accompanying drawings, forming a part hereof.

Our invention has relation to improvements in elevator safety appliances; and it consists in the novel construction and arrangement of parts more fully set forth in the specification and pointed out in the claims.

In the drawings, Figure 1 is a side elevation of our invention with parts broken away, showing also an elevation of the cage or car and the elevator-shaft. Fig. 2 is a top plan view of the drum and pumps and their connections; and Fig. 3 is a vertical section on line 3 3 of Fig. 1, taken through the pipes leading from the pump-cylinder.

The present invention is an improvement both on the construction shown in United States Letters Patent granted to us under date of November 20, 1900, numbered 662,264, and on that disclosed in our pending application, Serial No. 31,690, filed October 1, 1900, the new device combining the advantages of both the aforesaid constructions, but eliminating the objectionable features thereof, among them being the tendency under ordinary conditions for the cage to travel unevenly and sometimes with a jerky motion, this objection resulting from the reciprocations of the pump-piston actuated by the travel of the cage. In the present device the cage travels evenly under all circumstances.

In detail the invention may be described as follows:

Referring to the drawings, 1 represents an elevator-shaft, and 2 the cage or car traveling therein, the pulling-cable being designated by 3. Mounted to one side of the bottom of the shaft is a revolving drum 4, over which are wound several wraps of a cable 5, one end of which passes over a lower guiding-sheave 6 and is connected to the bottom of the elevator-cage, the other end passing over a

guiding-sheave 7 at the top of the shaft and connected to the top of the cage to one side of the point of connection of the pulling-cable 3. From the connections described it is apparent that with the upward travel of the cage the latter will draw upon one end of the cable 5 and with the descent of the cage the latter will pull upon the opposite end of said cable 5, thus imparting rotation to the drum at all times. A sufficient number of wraps of the cable 5 are first passed about the drum to prevent slipping of the cable when either end thereof is under tension during the travel of the cage.

Carried by either or both ends of the drum-shaft is a crank-arm 8, coupled by a connecting-rod 9 to the piston-rod 10 of an oil-cylinder C, secured to the base-plate of the engine, the walls of the cylinder being tapped above and below the limits of the piston's stroke by pipes 11 11', respectively, the opposite ends of said pipes communicating with a vertical pipe 12, communicating with the bottom of an open oil vessel or receiver 13. Communicating with the pipes 11 11' are branch pipes 75 or shunts 14 14', respectively, the opposite ends of said shunts coupling with an oil-discharge pipe 15, communicating with the vessel 13 at a point below the surface of the oil contained therein. The pipes 11 11' are provided at a point exterior to the shunts 14 14' with inwardly-swinging gate-valves 16 16', respectively, and the shunts are provided with check-valves 17 17', all of ordinary constructions, but shown in section in the drawings. Above the upper shunt the pipe 15 is provided with a regulating valve or cock 18 of the ordinary faucet type, the particular position to which the same has been set determining the rapidity of flow therethrough of the oil forced by the piston of the pump-cylinder into the receiver 13. Beyond the regulating-cock 18—that is, between it and the receiver 13—the pipe 15 is provided with an emergency or pressure-regulating valve 95 19, also of the well-known construction and shown herein in section.

The operation of the device is as follows: With the travel of the cage in either direction the pump will be set into operation, the

piston first driving the oil in one direction and then the other, the latter always discharging into the open vessel or receiver 13. With the downward stroke of the piston the gate-valve 16' is forced to a closed position and the gate-valve 16 opens, allowing the oil from the receiver 13 to follow the piston in such down-stroke. The oil below the piston is forced through the pipe 11', shunt 14', past the check-valve 17', (the valve 17 closing under the circumstances,) through the pipe 15' past the valves 18 and 19, into the receiver 13. With the upstroke of the piston the gate-valve 16 is forced to a closed position, the gate-valve 16' opening and allowing the oil from the receiver 13 to follow the piston in such upstroke. The oil above the piston is forced through the pipe 11, shunt 14, past the check 17' (the check 17' closing under the circumstances,) through the pipe 15, past the valves 18 and 19, into the receiver 13. The valve or cock 18 is set or opened sufficiently to allow for the uninterrupted flow of the oil past it at a rate commensurate with the normal speed of the cage, the emergency-valve 19 being open to its full extent, so as not to interfere with such flow. Should the cage for any reason become overloaded, however, and the valve 18 become insufficient to resist any abnormal flow under the circumstances, the excess of pressure of the oil will then tend to partially or wholly close the emergency-valve, (being virtually a pressure-regulating valve,) thus allowing the oil to discharge at a rate which will either check a too-rapid descent of the cage or stop it altogether, thus indicating that the same has been overloaded. The spring of the emergency-valve can be set to any tension, as is obvious.

With our present apparatus the cage is permitted to travel without any perceptible jerks, a uniform and even travel being always insured, one reason for this result being the fact that the oil is always discharged into an open vessel and not forced back and forth from one end of the cylinder to the other, as is the case of the construction described in our pending application above referred to.

It is apparent, of course, that the present device may be used in connection with any character of elevators, hoisting apparatus, inclined railways, and the like. It is further apparent that minor changes may be resorted to without departing from the spirit of our invention.

Having described our invention, what we claim is—

1. In an elevator safety appliance, a cage or car, a liquid-pump located at a point removed from the cage, a drum mounted in connection with the pump, a cable wound about the drum and having its opposite ends secured to the cage, means for guiding said cable, intermediate connections between the drum and pump for operating the latter upon the travel of the cage in either direction, and a vessel for receiving the liquid operated by

the pump with each stroke of the piston thereof, substantially as set forth.

2. In an elevator safety appliance, a cage or car, a liquid-pump located at a point removed from the cage, a drum mounted in connection with the pump, a cable wound about the drum and having its opposite ends secured to the cage, means for guiding said cable, intermediate connections between the drum and pump for operating the latter upon the travel of the cage in either direction, and an open vessel for receiving the liquid operated by the pump substantially as set forth. 75

3. In an elevator safety appliance, a liquid-pump adapted to be operated by the cage during its travel in either direction, a vessel for holding and receiving the liquid operated by the pump, a series of pipes leading from the pump-cylinder, one on each side of the limits of the stroke of the piston and connecting with the vessel, a valve in each pipe for permitting the flow of the liquid from the vessel behind the piston during the reciprocations of the latter, a shunt leading from each of the aforesaid pipes, a discharge-pipe communicating with said shunts and with the vessel, check-valves in said shunts, and a regulating valve or cock in said discharge-pipe located at a point between the adjacent check-valve and vessel, the parts operating substantially as and for the purpose set forth. 80

3. In an elevator safety appliance, a liquid-pump adapted to be operated by the cage during its travel in either direction, a vessel for holding and receiving the liquid operated by the pump, a series of pipes leading from the pump-cylinder, one on each side of the limits of the stroke of the piston and connecting with the vessel, a valve in each pipe for permitting the flow of the liquid from the vessel behind the piston during the reciprocations 95 of the latter, a shunt leading from each of the aforesaid pipes, a discharge-pipe communicating with said shunts and with the vessel, check-valves in said shunts, and a regulating valve or cock in said discharge-pipe located at a point between the adjacent check-valve and vessel, the parts operating substantially as and for the purpose set forth. 96

4. In an elevator safety appliance, a liquid-pump adapted to be operated by the cage 105 during its travel in either direction, a vessel for holding and receiving the liquid operated by the pump, a series of two pipes leading from the pump-cylinder, one on each side of the limits of the stroke of the piston and communicating with the vessel, a gate-valve in each pipe for permitting the flow of the liquid from the vessel behind the piston during the reciprocations of the latter, a shunt leading from each of the aforesaid pipes, a discharge-pipe communicating with said shunts and with the vessel, check-valves in said shunts, a regulating valve or cock in said discharge-pipe located at a point between the adjacent check-valve and the vessel, and an 115 emergency-valve in the discharge-pipe located between the regulating-valve and the vessel, the parts operating substantially as and for the purpose set forth. 116

5. In an elevator safety appliance, a cage 120 or car, a liquid-pump connected thereto and operated thereby during the travel of the cage in either direction, and a vessel connected with the pump-cylinder for receiving the liquid operated by the pump with each stroke 125 of the piston, substantially as set forth.

6. In an elevator safety appliance, a cage or car, a liquid-pump located at a point removed from the cage, a drum mounted in connection with the pump, a cable wound about the drum and having its opposite ends secured to the cage, intermediate connections between the drum and pump for operating the latter upon the travel of the cage in either

direction, and a vessel for receiving the liquid operated by the pump, substantially as set forth.

7. In an elevator safety appliance, a cage or car, a liquid-pump located at a point removed from the cage, a drum mounted in connection with the pump, a cable wound about the drum and having its opposite ends secured to the cage, intermediate connections between the drum and pump for operating the latter upon the travel of the cage in either direction, and a vessel for receiving the liquid operated by the pump with each stroke of the piston thereof, substantially as set forth.
- 10 8. In an elevator safety appliance, a cage or car, a liquid-pump located at a point re-

moved from the cage, a drum mounted in connection with the pump, a cable wound about the drum and having its opposite ends secured to the cage, intermediate connections between the drum and pump for operating the latter upon the travel of the cage in either direction, and an open vessel for receiving the liquid operated by the pump, substantially as set forth.

20 25 In testimony whereof we affix our signatures in presence of two witnesses.
